ATTORNEY.

UNITED STATES PATENT OFFICE.

LEWIS E. TOWERS, OF DETROIT, MICHIGAN, ASSIGNOR OF ONE-THIRD TO JOHN A. MCKINLEY AND ONE-THIRD TO LEE TERWILLINGER, BOTH OF DETROIT, MICHIGAN.

COLLAPSIBLE BOAT.

Application filed July 22, 1921. Serial No. 486,748.

To all whom it may concern:

Be it known that I, LEWIS E. TOWERS, citizen of the United States, residing at Detroit, county of Wayne, State of Michigan, have invented a certain new and useful Improvement in Collapsible Boats; and declare the following to be a full, clear, and exact description of the same, such as will enable others skilled in the art to which it pertains to make and use the same, reference being had to the accompanying drawings, which form a part of this specification.

My invention relates to a collapsible boat so constructed that the boat may be collapsed into a substantially flat shape so that several boats may be piled one upon another within a comparatively small space and it is particularly adapted for life saving boats to be carried by passenger vessels.

An object is to provide a simple, inexpensive type of collapsible boat of suitable, sturdy construction and easy of operation.

A further object is to provide a boat, the frame work of which is of such a character that it may be collapsed together and which frame work is provided with a flexible, outer covering or skin which will yield to conform with the relative change in position of the frame work.

A further object is to provide a fabric-covered boat, the opposed gunwale sections of which are adapted to fold together and the floor of which is adapted to be tilted to lie in substantially the same plane as the gunwale sections and keel.

These and other objects, together with details of construction, will more fully appear from the following description, appended claims and accompanying drawing, in which:

Figure 1 is an elevation of my improved boat.

Fig. 2 is a plan view of my invention.

Fig. 3 is a cross-section taken on line 3-3, Fig. 2.

Fig. 4 is a fragmentary section of the joint between the keel and gunwale sections.

Fig. 5 is a cross section taken on line 5-5 of Fig. 4.

My invention comprises a collapsible boat provided with a folding skeleton framework, over which is stretched a fabric or other suitable flexible covering *a*.

The framework comprises a keel *b*, turned up at opposite ends to form the stem and stern, which keel is here shown as formed of hollow tubing into each open end of which is fitted an L-piece *c*, the horizontal, extending arm of which L-piece is hollow and preferably rectangular in cross-section, as shown in Fig. 5. Vertical spacer pins *d* and *d*² extend through the horizontal arm of this L-piece providing a pocket on each side thereof within which is received the ends of the opposite gunwale sections *e* and *e*² which have a permitted longitudinally slidable movement within said pockets. Each gunwale section is provided at the end received in the aforementioned pocket with a longitudinally-extending slot *f* through which passes a fixed pin *g*, which pin is carried by the L-piece *c*. The gunwale sections are preferably made of resilient material so that they may bend outwardly in the middle, as shown in Fig. 2, when the boat is in the open position.

Each gunwale section carries a series of flexible ribs *h* which extend downwardly, but do not reach to the keel and may be turned slightly inwardly at their lower ends to prevent tearing of the outer covering of the boat. With the exception of the middle rib, these ribs are not secured to the keel but are secured together in spaced relationship by means of a cable *i* extending from stem to stern. The middle ribs *h*² are substantially larger than the intermediate ones on either side thereof and are secured at their lower ends to the keel by means of a flexible cable *k*. These middle ribs are connected together intermediate their ends by a hinged thwart *m* adapted to break in the middle when the opposite gunwale sections are folded together, being raised upwardly at such middle point. The proximate ends of the separate thwart sections are pivoted by means of a pintle *m*². The outer ends of the thwart sections are pivoted to the ribs *h*² by means of pintles *m*³, as shown in Fig. 3.

The separate thwart sections are adapted to be locked in the open position by means of a latch-bolt *n* carried in a recess formed in one thwart section, which bolt is provided with a catch *n*² by means of which the same may be retracted against the resistance of a spiral spring *o*, which is adapted to hold the bolt outwards. When the bolt is

retracted the catch n^2 may be engaged in a slot n^3 so as to hold the bolt in the withdrawn position. When the bolt is released to the action of the spring o , and the thwart sections are open, as shown in Fig. 3, the bolt engages in a striker recess formed in the opposite thwart section and locks the separate sections together as shown in the drawing.

10 I provide a floor p pivoted at opposite ends by means of pintles q which are mounted for vertical travel in fixed links or vertically slotted uprights s so that the floor may be tilted about said pintles, which 15 pintles have a permitted vertical movement of travel within the slot in the upright s to accommodate the floor to the opening and folding of the boat.

20 A link t is pivoted at one end to one side of the floor, and at the other end, by means of a longitudinal slot within which travels the projecting end of the pintle m^2 , to the thwart sections at their hinge so that when 25 the thwart sections are folded upwardly and together the floor tilts about the pintles q . The thwart m is adapted to also serve as a seat.

30 It is apparent that oar locks might be provided as desired and that other improvements and variations in details of construction might be made within the scope of the specification and claims; applicant having 35 illustrated merely the skeleton framework and outer covering of the boat.

35 What I claim is:

1. In a collapsible boat, a framework provided with a flexible outer covering, said framework comprising a keel provided at stem and stern with a pair of adjacent 40 sockets extending lengthwise the keel, opposed resilient gunwale sections, opposite ends of which are disposed in said sockets

for slidable movement upon bending said gunwale sections to bow their middle portions outwardly, resilient ribs depending 45 from said gunwale sections, releasable means for holding said gunwale sections bowed outwardly from one another at their middle.

2. A folding boat comprising a skeleton 50 framework over which is stretched a flexible covering, which framework comprises a keel piece turned upwardly at the ends to form the stem and stern, gunwale sections of resilient material having slidable connection 55 with said stem and stern to move relatively thereto to permit flexing of said gunwale sections to bow them outwardly intermediate their ends, a thwart pivoted at opposite ends to said gunwale sections and hinged intermediate its ends to fold upwardly between 60 said gunwale sections.

3. The combination in a boat provided with a flexible outer covering, of a framework therefor comprising a keel turned up 65 at opposite ends and provided at each end with angularly projecting sockets extending inwardly lengthwise the keel, a pair of opposed resilient gunwale members opposite ends of which are received in said sockets 70 for endwise slidable movement therein, a floor pivoted at each end to the keel for tilting movement about a horizontal axis, folding means interposed between said gunwale sections at their middle to hold them 75 bowed outwardly from each other, linkage connecting said folding means with said floor to tilt the floor to a substantially horizontal position when said folding means is unfolded to hold the said gunwale members 80 bowed outwardly from each other.

In testimony whereof, I sign this specification.

LEWIS E. TOWERS.
